UNITED STATES PATENT OFFICE.

GUSTAF ARVID ANDERSON, OF WAYNESBOROUGH, PENNSYLVANIA,
ASSIGNOR TO THE GEISER MANUFACTURING COMPANY, OF SAME
PLACE.

BOILER.

SPECIFICATION forming part of Letters Patent No. 536,058, dated March 19, 1895.

Application filed December 1, 1894. Serial No. 530,612. (No model.)

To all whom it may concern:

Be it known that I, GUSTAF ARVID ANDERSON, a subject of the King of Sweden and Norway, residing at Waynesborough, in the county of Franklin and State of Pennsylvania, have invented certain new and useful Improvements in Boilers; and I do hereby declare the following to be a full, clear, and exact description of the invention, such as will enable others skilled in the art to which it appertains to make and use the same.

This invention relates to steam boilers and more particularly to those boilers used for traction or road engines; and it consists of a protector for the crown sheet, as hereinafter fully described and claimed, for preventing the water level from becoming lower than the crown sheet when the engine is going down hill.

20 In the drawings: Figure 1 is a longitudinal section through a boiler provided with a crown sheet protector according to this invention. Fig. 2 is a cross-section through the boiler taken on line $x-x$ in Fig. 1. Fig. 3 is a similar cross section taken on the line $y-y$ in Fig. 1.

The boiler is of ordinary approved construction, and A is the crown sheet of its fire box. The line $b-b$ indicates the ordinary water level 30 when the engine is on level ground, and the line $c-c$ indicates what the water level would be if the engine were proceeding down a hill and the protector were not used.

In order to protect the crown sheet from being uncovered and burned by the heat of the fire in the fire box a steam chamber B is provided. This chamber B is supported inside the barrel of the boiler, over the tubes, by brackets B' or any similar fastening devices 40 which will secure it in position. The upper part of the chamber B is preferably curved to conform to the shape of the top part of the boiler but its exact form is not material. The bottom portions $b'-b'$ of the chamber B are substantially flat and incline upward longitudinally toward the smoke box end of the boiler to conform to the inclination of the top row of fire tubes.

50 A channel C is formed longitudinally in the under side of the chamber B, the bottom plate being bent upward to form the sides and top

of the channel. This channel is narrow at the smoke box end of the boiler and becomes wider as it approaches to fire-box end.

D is a head forming the rear end of the 55 chamber. E is a head which forms the front end of the chamber, and is provided with a lip e having one or more openings e' at its top which is near the top of the boiler.

F is a conical ring secured to the upper 60 part of the rear end of the chamber and projecting through a hole in the shell of the boiler into the steam dome f. The ring is made to fit the hole tightly, but an absolutely steam tight joint need not be formed between 65 the parts.

G are drain pipes projecting from the head D and extending over the fire box.

A single longitudinal channel arranged centrally of the chamber is preferred, but more 70 than one channel may be used if desired.

When the engine proceeds down hill the water level is changed and becomes as indicated by the line $d-d$ in Fig. 1. The flat bottom portions $b'-b'$ of the chamber incline laterally in opposite directions at the sides of the central channel, the inclination being downward from the channel toward the shell of the boiler. The water presses against the bottom portions of the chamber and is forced 80 forward onto the crown sheet which does not become uncovered. The steam formed in the boiler over the tubes rises against the inclined bottom portions $b'-b'$ and passes into the channel C, the inclined sides of which permit it to escape freely into the steam space over the crown sheet, so that priming does not occur.

The steam passes downward through the openings e' in the head E, through the chamber C and upward into the steam dome, whence it is conducted to the engine through a steam pipe in the ordinary way.

Any water which may pass into the chamber C with the steam collects in the bottom part 95 of the chamber and is discharged through the drain pipes G when the engine commences to go up hill.

What I claim is—

1. The combination, with a boiler, of a chamber 100 provided with a head at each end and a longitudinal channel in its under side, ar-

ranged in the barrel of the boiler, and operating to prevent the water from leaving the crown sheet, substantially as set forth.

2. The combination with a boiler of a chamber arranged in the barrel of the boiler and provided with a longitudinal channel in its under side, a steam outlet ring projecting through a hole in the boiler shell into the dome, and a steam inlet opening near the top 10 of the chamber, substantially as set forth.

3. The combination, with a boiler, of a chamber arranged in the barrel of the boiler and provided with a longitudinal channel in its

under side, the sides of said channel being divergent and wider apart at the fire box end, 15 and the bottom portions of the chamber being downwardly and laterally inclined from the channel toward the boiler shell, whereby a free escape for the steam is provided, substantially as set forth.

In testimony whereof I affix my signature in presence of two witnesses.

GUSTAF ARVID ANDERSON.
